(57) **CLAIM**

I claim the ornamental design for a bottled water dispenser, as shown and described.

DESCRIPTION

FIG. 1 is a front view of a bottled water dispenser of the present invention;

FIG. 2 is a left side view of the bottled water dispenser of FIG. 1;

FIG. 3 is a right side view of the bottled water dispenser of FIG. 1;

FIG. 4 is a top plan view of the bottled water dispenser of FIG. 1; and,

FIG. 5 is a perspective view of the bottled water dispenser of FIG. 1.

The broken lines in the drawings are included for the purpose of illustration and form no part of the claimed design.
